METHOD FOR SECURING TERMINALS

Henry F. Hild and Siegfried E. Manecke, Indiana, Pa., assignors to Robertshaw-Fulton Controls Company, Richmond, Va., a corporation of Delaware
Filed Oct. 2, 1959, Ser. No. 844,100
4 Claims. (Cl. 29—155.55)

This invention relates to method for securing terminals to a casing and, more particularly, to securing flat plate male terminals to a molded plastic casing.

It has been the practice to secure a flanged electrical terminal to a relatively thin-walled casing by overlapping portions of the terminal so as to engage one surface of a wall. Generally, this practice of securing a terminal to a casing has been referred to as "staking."

To secure the flanged terminal to an aperture in the casing, a sharp-edged punch is used to overlap a portion of the body of the terminal, closely adjacent to the periphery of the aperture in the casing wall, so as to form outwardly extending flanges which secure the terminal to the wall. However, as the terminal is generally made of a malleable metal, such as brass, it is relatively soft and easily split when subjected to shearing stresses. In addition, the sharp-edged punch used for peeling the terminal is not resiliently mounted and, therefore, transmits a high impact shock to the terminal when the sharp-edged punch is actuated.

Another difficulty in staking terminals to a thin-walled casing is the extreme accuracy with which the sharp-edged punch must be positioned prior to actuation. Generally, the punch has at least two edges that engage substantially oppositely disposed side portions of the terminal. If the punch is not properly positioned, one edge will engage the associated side portion of the terminal; while the other edge will engage the surface of the wall of the casing. In this event, the casing can easily be broken by the impact. Also, should the punch initially be positioned to unevenly engage opposite sides of the terminal, then uneven stresses will be imposed upon the terminal upon impact. These uneven stresses will be transmitted to the casing to crack the thin wall upon which the terminal is mounted.

An object of this invention is to secure terminals to a thin-walled casing by peening a portion of the terminal onto the surface of the casing.

Another object of this invention is to spin a shoulder portion of a terminal onto the upper surface of a thin-walled casing under a relatively light, uniformly distributed impact operation.

A further object of this invention is to fasten electrical terminals to a thin-walled casing in a rapid, inexpensive manner.

Other objects and advantages will be apparent from the following description of the invention taken in connection with the accompanying drawings wherein:

FIG. 1 is an elevation view, partly in section, of a terminal positioned in a thin-walled casing;

FIG. 2 is a view similar to FIG. 1 of the terminal and punch;

FIG. 3 is a view of the terminal and punch in operative relationship;

FIG. 4 is an end view, partly in section, of the terminal and punch after the spinning and peening operation; and

FIG. 5 is a plan view of the terminal after the spinning and peening operation.

Referring more particularly to FIG. 1, there is shown a flat terminal post 10 inserted and positioned in a slit aperture 12 of a thin-walled casing 14. Thin-walled casing 14 can be molded from any known phenolic plastic having good structural and electrical insulation properties. The terminal 10 is stamped out of a flat sheet material,

2

such as brass, and may have various configurations, one of which is shown in FIG. 1. The terminal 10, shown in FIG. 1, has a male connector portion 16 extending upwardly of the aperture 12 in the casing 14. The male connector 16 has a length and width of suitable dimensions, which dimensions are primarily determined by the female connector (not shown) that will be used in the electrical circuit.

A main body portion 18 of the terminal 10 is located beneath the male connector portion 16 of the terminal 10 and substantially between the sidewalls 20 of the aperture 12. The main body portion 18 has a width which is slightly greater than the base width of the male connector portion 16. The depth of the main body portion 18 of the terminal 10 is greater than the thickness of the wall of the casing 14. A small area on each side of the main body portion 18 extends above the upper surface 22 of the wall of the casing 14, to form shoulders 24.

Beneath the main body portion 18 of the terminal are oppositely disposed flange portions 26 which extend outwardly from the longitudinal length of the terminal 10. The flange portions 26 of the terminal 10 are of sufficient width and depth to prevent the terminal 10 from being inserted completely through the aperture 12 in the thin wall of the casing 14.

Beneath the main body portion 18 and the flanged portions 26 of the terminal 10, there is a downwardly extending projection. This projection of the terminal 10 is the terminal connector 28 to which electrical conductors (not shown) can be secured by numerous means, one of which is soldering. The terminal connector 28 can have numerous configurations, but for representative purposes is substantially rectangular.

A jig 30 is shown by dotted line configuration in FIG. 1. The jig 30 can be of any known type and is used primarily to support and position the terminal 10 in the aperture 12 so that the upper edges 32 of the flanges 26 of the terminal abut against the lower surface 34 of the thin-walled casing 14.

As shown in FIG. 2, a cylindrical punch 36, having a concentric cylindrical cavity 38 bored in the central portion of the punch 36, is depicted as being partially lowered over the male connector portion 16 of the terminal 10.

Edge 40 is formed at the junction of a cylindrical surface 39 of the cavity 38 and a bottom beveled surface 42 of punch 36. Beveled surface 42 is of frusto-conical form being inclined at a slight angle relative to a plane normal to the axis of rotation of the punch 36. The angular inclination of the beveled surface 42 will depend upon the material from which the terminal is made. Edge 40 will engage the upper edge 44 of the shoulder 24 immediately adjacent to the base width of the male connector portion 16, when there is a downward motion of punch 36. Edge 40 will cut into shoulder 24, and beveled surface 42 will peel the cut metal outwardly.

It will also be apparent that the cavity 38 of the punch 36 must be cylindrical in form. The diameter of the cavity 38 is determined by the amount of material to be peeled from the shoulder 24 of the terminal 10, and the width of the male connector 18 of the terminal 10.

In FIG. 2, the circular punch 36 is diagrammatically shown as being resiliently mounted by means of spring 46. Punch 36 is mounted to a drive mechanism (not shown) that will rotate or spin punch 36 at variable speeds; and, in addition, the drive mechanism imparts a rectilinear reciprocating motion to punch 36 so that the punch has rapid longitudinal movement in two directions. The spring 46 will limit the impact pressure of punch 36 in the downward direction to a constant value.

As shown in FIG. 3, a quick, rapid, light impact blow of punch 36 in the downward direction combined with

the spinning action of punch 36 will evenly peel and peen the shoulder portion 24 of the main body 18 of the terminal 10 away from the male connector portion 16. The beveled edge 42 of the punch 36 will curl the peeled shoulder portion 24 over so as to form an upper flange 48 to the main body 24 of the terminal 10. It is to be noted that the curled and peened shoulder 24 will form a flange 48 on the upper surface 22 of the wall of the casing 14.

The jig 30 will force the flange 26 of the terminal 10 into engagement with the lower surface 34 of the thin-walled casing 14 to insure proper engagement with the lower surface 34 of the wall. In addition, the peeling and spinning action of the punch 36 will draw as much of the shoulder portion 24 of the main body 18 of the terminal 10 out of the aperture 12 as is exposed to further insure a tight engagement between the upper surface 32 of the terminal flange 26 and the lower surface 34 of the thin-walled casing 14. The action of the resilient spring 46 on the punch will equalize the pressure on the beveled edge 42 to thereby insure that each peened shoulder 48 will be subjected to the same light oscillatory impact motion of the punch 36; and, in addition, to the spinning motion of the punch.

The male terminal 10 is shown in FIG. 4, with the punch 36 partially withdrawn from its lowermost stroke. It is to be noted that the peened shoulder 48, due to the spinning action, overlaps the upper surface 22 of the casing 14 immediately adjacent to the aperture 12 so as to form a tab 50 which is not in alignment with the flat surface of the terminal 10. For purposes of representation, the peened shoulders in FIGS. 3 and 4 have been enlarged relative to their true representations. In actuality, the uppermost portion 52 of the peened shoulder is substantially level with the upper surface 22 of the casing 14 and could be considered as being flared into the upper surface of the casing.

As shown in FIG. 5, the peened shoulder 48 is spread out over the adjacent surface of the thin-walled casing 14, and is, in effect, twisted slightly from the flat plane of terminal 10 so that the terminal 10 cannot be withdrawn from the aperture 12.

Although not shown in the drawings, it will readily be apparent that a substantially circular terminal having a circular shoulder about the male connector portion of the terminal could also be subjected to the action of the punch as previously described. The circular terminal will have its shoulder spread out to overlap the area immediately adjacent to a circular aperture in the thin-walled casing.

In addition, it is to be realized that numerous terminals can be mounted in a single jig, so that each terminal is inserted through an appropriate aperture in the casing. In this manner, several punches can be mounted on one drive mechanism so that the numerous terminals can be fastened to the casing in one operation.

While only one embodiment of the invention has been shown and described herein, it will be apparent that numerous modifications and changes can be made without departing from the scope of the invention as defined in the appended claims.

We claim:

1. The method of securing a flanged terminal post in an apertured casing wall which comprises, position-

ing the terminal with the flange abutting against the casing wall and the terminal post projecting through the aperture and outwardly of the wall, simultaneously cutting and spinning the projecting portion of the terminal post away from the main body thereof until the spun portion engages the casing wall, and further cutting and spinning the projection portion while simultaneously peening the spun portion into evenly stressed engagement with the casing wall.

2. The method of securing a flanged terminal post in an apertured casing wall which comprises, positioning the terminal with the flange abutting against the casing wall and the terminal post projecting through the aperture and outwardly of the wall, simultaneously cutting and spinning the projecting portion of the terminal post until the spun portion curls toward and engages the casing wall and further cutting and spinning the projecting portion while simultaneously peening the spun and curled portion of the terminal post into evenly stressed engagement with the casing wall.

3. The method of securing a flat plate flanged terminal post in a slit aperture in a casing wall which comprises, positioning the terminal with the flange abutting against the casing wall and the terminal post projecting through the aperture and outwardly of the wall, simultaneously cutting and spinning oppositely disposed projecting portions of the terminal post until the spun portions engage said casing wall, to overlap the longitudinal ends of the slit aperture, and further cutting and spinning the projecting portions while simultaneously peening the spun portions of the terminal post into evenly stressed engagement with the casing wall closely adjacent to the longitudinal ends and sides of the slit aperture.

4. The method of securing a flat plate flanged terminal post in a slit aperture in a casing wall which comprises, positioning the terminal with the flange abutting against the casing wall and the terminal post projecting through the aperture and outwardly of the wall, simultaneously cutting and spinning oppositely disposed shoulder portions of the terminal post until the spun portions curl toward and engage the casing wall, to overlap the longitudinal ends of the slit aperture, and further cutting and spinning the projecting portions while simultaneously peening the spun and curled portions of the terminal post into evenly stressed engagement with the casing wall.
